UNITED STATES PATENT OFFICE.

SAMUEL SEVERSON, OF VALDERS, WISCONSIN.

HAIR-CUTTING APPLIANCE.

1,423,363.

Specification of Letters Patent. Patented July 13, 1922.

Application filed May 18, 1920. Serial No. 332,236.

To all whom it may concern:

Be it known that I, SAMUEL SEVERSON, a citizen of the United States, and resident of Valders, in the county of Manitowoc and 5 State of Wisconsin, have invented certain new and useful Improvements in Hair-Cutting Appliances; and I do hereby declare that the following is a full, clear, and exact description thereof.

10 My invention relates to new and useful improvements in hair cutting appliances of that type in which the cutters are mechanically operated.

It is in general the object of this invention to provide a very simply constructed and readily manipulated hair cutting appliance which is capable of trimming hair to any desired length and for cutting any length of hair with great facility.

20 It is also an object of the invention to provide a device of this character having cutting members which can be automatically shifted to cut hair of different lengths, or which can be retained stationary to trim 25 hair of the same length.

Still another object of the invention is to provide an appliance of this nature having means for evenly drawing the hair to be cut into range of the cutting members.

30 With these general objects in view the invention consists in the novel features of construction, combination and arrangement of parts which will be hereinafter more particularly described and claimed.

35 In the accompanying drawing:

Figure 1 represents a longitudinal sectional view taken substantially on the plane of the line 1—1 of Figure 2.

Figure 2 is a part side elevational and 40 part sectional view of the appliance.

Figure 3 is a transverse sectional view through the gear housing; and

Figure 4 is a similar sectional view taken on the plane of the line 4—4 of Figure 2.

45 In the preferred embodiment of the invention as illustrated in this drawing, the reference character 1 denotes an elongated substantially rectangular casing open at both ends and having its sidewalls at its intake 50 end extending beyond the adjacent edges of the other walls to provide spacing fingers 2. The opposite end of the casing is closed by a removable cover 3 secured thereto by screws or the like 4. The cutter comprises a carrying plate 5 slidable in the casing 1 and engaging the inner surface of the several walls thereof, a relatively stationary cutter

bar 6, and a reciprocable cutter bar 7. As is customary in this type of cutter, the bars 6 and 7 are provided along one longitudinal edge with co-operating cutter teeth 8 and 9, the latter being shifted into and out of alignment with the teeth 8 upon reciprocation of the cutter bar 7. The last mentioned cutter bar is disposed between the carrying plate 5 and the stationary cutter bar 6, it being held in operative position with respect thereto by retaining bolts 10, the same extending transversely through the several parts of the cutting member and having nuts 11 on their threaded ends. Springs 12 are located between the carrying plate 5 and the nuts 11 to procure a yieldable engagement between the cutter bars and the plate 5. The carrying plate 5 also provides 75 a bearing 13 for one end of a feed shaft 14 which extends longitudinally through the casing 1 and has an eccentric 15 at one end disposed in an opening in the cutter bar 7. Thus rotation of the shaft 14 turns the eccentric and reciprocates the bar 7, this being permitted in view of the bolts 10 being disposed in the slots 10'.

The end portion of the feed shaft 14 opposite the end carrying the eccentric 15 is 85 rotatably journaled in the cover 3 and is slidable longitudinally through the hub 16 of a worm gear 17, the same being splined thereto by means of a feather and the key groove 18.

90 The worm gear 17 is rotated by means of a worm 19 formed on the stub shaft 20; the latter extending transversely of the casing 1 and having a suitable flexible shaft 21 connected thereto for rotation from a suitable source of power. The hub 16 of the worm gear 17 is journaled in a bearing carried by a wall 22 which partially defines a gear housing 23, one side of said housing being closed by said cover 3 and two of the other sides by the walls of the casing 1.

95 From this construction it will be seen that rotation of the stub shaft 20 causes the feed shaft 14 to be revolved with a consequent actuation of the cutter bar 7. The 105 rotation of the feed shaft 14 is used for moving the same longitudinally through the casing 1 so as to shift the cutter member including the parts 5, 6 and 7. In other words the gear housing 23 contains a slidable feed plate 24, one end of which is bifurcated and has the shaft 14 disposed between its furcations 25 and adapted to be engaged by a thread portion 26 at the will of the operator.

The opposite or outer end of the plate 24 extends through an opening in the casing 1 and is bent laterally to provide a finger piece 27. An expanding leaf spring 28 located between the finger piece and the adjacent wall of the casing 1 normally urges the feed plate outwardly to disengage the thread portion 26 from the threads of the feed shaft 14. During such disengagement the shaft 14 merely rotates and the cutter member is held against shifting longitudinally of said casing. On the other hand, as soon as the operator forces the thread portion 26 into engagement with the threads of the shaft 14, the rotation of the latter causes the same to be fed outwardly of the casing. In Figures 1 and 2 the shaft has been partially fed from the casing to space the cutter member inwardly of the intake end of the latter. As shown in Figure 1 the feed plate 24 is slidably in guides 29 carried by the cover 3.

The casing 1 adjacent the closed end thereof is provided with a suction tube attaching nipple 30 whereby the interior of the casing may be subjected to the action of a suitable vacuum mechanism (not shown.) That is to say by such an arrangement air is drawn through the casing from the open end thereof and through the cutter member. In order that this air may be drawn transversely across the cutter bars throughout the length thereof, the carrying plate 5 is formed with a longitudinally extending intermediate suction slot 31. This slot is positioned inwardly of the inner ends of the teeth 8 and 9 so that the air entering the casing 1 is deflected with a result that the hair is positively drawn through the teeth 8 and 9. As indicated at 32 the portion of the carrying plate 5 adjacent the teeth 9 is cut away to readily permit said hair to enter the slot 31. The carrying plate 5 also has friction elements 33 disposed in its ends for engagement with the side walls of the casing 1, such an arrangement being conducive to a more efficient operation.

In the use of my invention, the operator starts the rotation of the worm shaft 20 the same being connected to the flexible shaft 21 of said suitable source of power, whereupon the cutter 7 will reciprocate continuously. If short hair is to be cut, the cutter member is located at the extreme open end of the casing 1 between the fingers 2, and as it is desired to cut less and less hair, the cutter member is progressively moved into the casing merely by pressing upon the finger piece 27. However, if a particular length of hair is desired, the cutter member is moved into the casing a suitable distance and permitted to operate in this position as long as necessary, the feed plate 24 under such conditions being inactive.

Although the preferred embodiment of the invention is shown in the drawing and above described, it is to be understood that various changes may be made in the different parts of the appliance and in the proportions of its parts, without departing from the principles or sacrificing any of the advantages thereof.

I claim:

1. In an appliance of the class described, a casing, cutting mechanism therein, means for operating the cutting mechanism, and means simultaneously operable in synchronism with said last named means for withdrawing the cutting mechanism inwardly of the operating end of the casing.

2. In an appliance of the class described, a casing, cutting mechanism therein, means for operating the cutting mechanism, and means operable by said last named means for progressively moving the cutting mechanism inwardly of the operative end of the casing, simultaneously with the operation of said cutting mechanism.

3. In an appliance of the class described, a casing, cutting mechanism therein, means for operating the cutting mechanism, and means selectively operable by said last named means for shifting the cutting mechanism in one direction in the casing simultaneously with the operation of said cutting mechanism.

4. In an appliance of the class described, a casing, cutting mechanism therein, means for operating the cutting mechanism, and selective means operable simultaneously with the operation of the cutting mechanism for automatically shifting said cutting mechanism in one direction in the casing or manually in the reverse direction or holding the same stationary.

5. In an appliance of the class described, a casing, cutting mechanism therein, means for operating the cutting mechanism including a drive shaft, and means selectively operable by the shaft for shifting the cutting mechanism in one direction in the casing simultaneously with the operation of said cutting mechanism.

6. In an appliance of the class described, a casing, cutting means therein, means for operating the cutting means, including a rotary threaded drive shaft, and a member movable into engagement with the thread of the shaft to cause said shaft to be fed in one direction with respect to the casing as a result of its rotation, said cutting means being carried by the shaft.

In testimony that I claim the foregoing I have hereunto set my hand at Valders, in the county of Manitowoc and State of Wisconsin.

SAMUEL SEVERSON.
